WILLIAM C. HEATH AND FRANKLIN G. HOBART, OF BELOIT, WISCONSIN, ASSIGNEES
TO FAIRBANKS, MORSE & CO., OF CHICAGO, ILLINOIS, A CORPORATION OF ILLINOIS

PUMP

Application filed August 20, 1924. Serial No. 733,083.

This invention relates to improvements in pumps, and more particularly to improvements in deep well pumps employing an electric motor for driving purposes; and has as its objects economical manufacture, ease of testing, compactness and pleasing appearance.

Another object of our invention is the securing of a self-oiling pumping mechanism which is protected from dust and is quiet running with a minimum of friction.

Another object of our invention is to prevent the lubricant from the mechanism from getting into the well.

Another object of our invention is to provide a pumping mechanism which permits the removal of the well-pipe with operating rods, cylinder, etc., without disturbing the base containing the motor and other operating mechanism.

Our invention will be best understood from the following description and drawings showing a preferred form.

In the drawings Fig. 1 is a plan view of a pump embodying a preferred form of our invention; Fig. 2 is a sectional end view taken along the plane 2—2 indicated in Fig. 1; Fig. 3 is a fragmentary sectional elevation taken along the plane 3—3 indicated in Fig. 1; Fig. 4 is a sectional elevation taken along the plane 4—4 indicated in Fig. 1; and Fig. 5 is a sectional elevation taken along the plane 5—5 indicated in Figs. 1 and 4. Fig. 6 is a detail of the pump head.

Referring by numerals to the drawings, a vertical motor 5 is here shown driving the worm 6 through the vertical shaft 7 and coupling 8. This worm 6 engages a worm wheel 9, preferably mounted midway on a horizontal shaft 10, carried in the bearing 11, situated on either side of the worm wheel 9. Beyond the bearing there may be at each end of shaft 10 duplicate cranks 12. Each crank 12 drives by a connecting rod 13 onto a bell crank 14, swinging freely on a stationary shaft 15, the connecting rod 13 being attached to bell crank 14 by means of pin joint 16.

Each bell crank imparts a vertical movement to a piston-like slide 17, through a short connecting rod 18, there being a pin joint 19

for the attachment of the rod to the bell crank 14, and a pin joint 20 for the attachment of this rod to the slide 17. To the top of the two slides 17 is preferably fastened a cross bar 21 which carries a connection situated preferably midway between the two slides for the rigid attachment of a pump rod 22 extending downward into the well.

The foregoing comprises a preferred means for translating the high-speed rotating motion of the electric motor into a moderate speed reciprocatory motion suitable for deep well pumps.

A worm 6 is preferably carried in a lower bearing 23 and an upper bearing 24 in a frame 25. Integral with this same frame are the bearings 11 for the worm gear shaft 10, and the pin bearing 15, for the bell crank fulcrum. This frame 25 is preferably secured, either by bolting, casting or other means, to an upper plate or cover 26, on the upper portion of which is mounted the motor 5. Plate 26 forms a cover for a containing box 27, which cover is preferably oil tight. The box 27 may be partially or almost completely filled with lubricating oil. Box 27 preferably has two hollow projections in which are located the bell cranks and the lower end of the slides and their connecting mechanism. Between these projections is left an open cavity through which the pump rod 22 and well pipe and cylinder may be drawn without disturbing the container. In this space between the projection of the container and at the upper end of the well pipe may be located a differential plunger 28.

The plunger 28 preferably operates in a differential cylinder 43 which may be attached directly to the pump head 42. Below the cylinder 43 may be attached any suitable form of outlet fitting such as 44 adapted to receive the well pipe at 45, and any suitable form of outlet valve (not shown) at 46. An opening 47 may be provided, to be closed by any suitable form of plug or cover (not shown) to provide access to the outlet valve. In case the pump is to operate in a locality subject to heavy frosts, it is desirable to install the differential plunger and cylinder and the outlet fitting below ground in which case,

another head (not shown) corresponding to head 42 may be provided and the cylinder 43 and fitting 44 attached thereto, the differential plunger 28 being attached farther down 5 on the rod 22. By this means the operating mechanism may still remain above ground or in an accessible position, whereas the differential plunger and outlet fittings are placed below ground to prevent freezing.

10 While the pump is at rest there is always a certain amount of leakage up past the plunger 28 and into the cylinder space above it. In our device we preferably make the chamber in the pump head 42 with a substantially greater volume than the maximum displacement volume of the plunger 28, and also preferably provide a drain opening in the bottom of pump head 42. After the cylinder 43 becomes full of this leakage water, any 15 further leakage will be carried away by the drain 48 and on starting the pump there will be no overflow from the pump head 42 since the chamber is large enough to take care of the maximum amount of water displaced by 20 the plunger 28 from the cylinder 43.

As a means for centering the well pipe, the lower surface of the pump head 42 is preferably flanged and machined concentric with the cylinder 43 and is preferably arranged 30 to rest on the top edge of box 27 and fits loosely in a concentrically bored out portion of the bottom flange 50 of cover 26.

An air compressor 29 may be provided operated by bar 30 through arm 31. A side cover 32 and a top cover 33 may be used.

The electric motor may be mounted onto cover 26 by turning down the end plate 34 of the motor to a definite size so as to permit it entering an opening in the cover 26. The 40 motor may be held down by means of the bolt lugs 35, and between these bolt lugs may be situated openings to permit the circulation of air between the end plate 34 and the cover 26 so as to facilitate the ventilation of the 45 motor 5. A plate or other suitable device, preferably of sheet metal, may be provided to prevent the dust in this circulating air from getting down into the working parts. Plate 36 may be arranged to fit closely around the 50 motor bearing and to draw down with some force against a seat 37 on the cover 26.

The container or box 27 containing the operating mechanism submerged in lubricating oil may have a drain opening 38, while the entire top is open sufficiently so that the entire operating mechanism attached to cover 55 may be inverted into the box. This makes it possible to remove the entire operating mechanism from the box, and to run the same apart from the pump.

60 Provision may be made for the return of such lubricating oil as may work up past the slide or guides 17 by employing some means such as a passage 39 which leads back into space 40, from which such oil will drain back

65 into the container or box 27 around the upper worm shaft bearing 24.

Though our invention consists largely in the construction and arrangement of parts hereinbefore described and particularly pointed out in the claims, yet we do not limit our invention to the precise form, construction or arrangement of parts shown or the several parts thereof, inasmuch as various alterations may be made without departing 70 from the scope of our invention.

We claim:

1. In a pump power head, an enclosing chamber therefor, a structure comprising a cover for said chamber, and pump-operating mechanism depending below the cover into the chamber, said mechanism being supported by, and removable with the cover structure, and including a driving member and a pump-actuating member, said members extending 80 through the cover.

2. In a pump power head, an enclosing chamber, a structure removably supported by said chamber, comprising a cover having 85 openings therein, a motor, mounted on said cover, and pump-operating mechanism depending below the cover into the chamber, and removable with said cover, said mechanism including pump actuating members operating through the openings in said cover. 95

3. In a pump operating unit, an enclosure, a cover therefor, a source of rotary motion; for driving said unit, and means depending from the cover into said enclosure, for translating rotary motion into reciprocatory motion, and means extending through the cover 100 adapted for applying the translated motion.

4. In a pump operating unit, a chamber adapted to contain oil, a cover therefor, a source of rotary motion for driving said unit, a rotary drive shaft, extending vertically into said chamber, and means depending from the cover into said oil chamber, for translating rotary motion into reciprocatory motion, and a member extending vertically 105 from said chamber, adapted for applying the translated motion.

5. In a power head, a chamber having an opening for a driving member and an opening for a reciprocating power take-off member, said openings being in the same wall and in an upper portion of the chamber and pump-operating mechanism suspended within the chamber, adapted for connection with 115 said member, and adapted to be freely removed, as a unit, from said chamber.

6. In a power head, a chamber adapted to contain oil, a cover therefor, a rotary driving unit carried by the cover, and means depending from the cover for translating rotary motion from the driving unit, into reciprocatory motion, and adapted to be removed with the cover, said means including a driven member arranged for reciprocating move- 125 130

ment through the cover and adapted for connection with a pump or the like.

7. A pump operating unit including a motor, a chamber adapted to contain oil, a pump operating mechanism in said chamber, a shaft extending from the motor into the chamber, for driving the operating mechanism, a bearing for said shaft above the level of the oil in said chamber, a vertically reciprocating slide driven by said mechanism, said slide adapted to move into and raise the oil for use in said bearing, and an oil passage extending from a point adjacent said slide, and directed to said bearing.
- 15 8. In a pump operating unit, a chamber having a detachable closure portion adapted to contain a supply of oil and driving mechanism in said chamber, a worm shaft extending into said chamber for operating said mechanism, a plurality of bearings for said shaft, and a bracket serving as a mounting for said bearings, said bracket being carried at one side of said closure portion, and extending substantially from said closure portion to the opposite wall portion of the chamber.

9. In a pump operating device, an oil chamber, a cover therefor, pump operating means supported by said cover and including a slide, a guide engaging said slide, a bearing associated with the operating means and disposed above the oil and suspended from said cover, said slide being adapted to move into the oil of the chamber to apply oil directly to the guide and to raise the oil for use in said bearing, and means for directing oil from said guide to said bearing.

10. In a pump operating apparatus, an oil container, a cover therefor, pump operating means supported by the cover and including a bearing suspended from the cover and a slide adapted to move into the oil of said container and to raise the oil for use in said bearing, above the level of the oil, and means on said cover for conveying such oil to the bearing.

11. In a power head, a chamber, a bearing member adapted as a support for driving means and suspended into said chamber, driving means carried by said bearing for translating rotary into reciprocatory motion, slides associated with the driving means and adapted to extend into said chamber, connecting means between said slides and said translating means, and means for relating the slides to apparatus to be driven by the power head.

12. A power head including a driving unit, a hollow base distinct from, and serving as a support for the driving unit, operating mechanism within said base, and operatively connected with the driving unit, a cross head outside and above the base, associated with said mechanism to receive a reciprocating movement therefrom, and a connection on

said cross head for operatively relating the power head and apparatus to be driven thereby.

13. In a pump operating device, an oil containing chamber, substantially enclosing said device, a cross head outside of said chamber, slides rigidly attached to opposite ends of the cross head, and extending downwardly into the chamber; operating mechanism working in said oil containing chamber, a member attached to said cross head, between the slides and external to said oil containing chamber, and adapted for connection with a pump, or the like, to be driven.

14. In a pump driving apparatus, a chamber, an assembly of operating elements comprising a rotating member, means for translating rotary motion into reciprocatory motion, and a reciprocating member, operated from said translating means; a removable cover for said chamber, said assembly depending from said cover, into said chamber, and means extending through said cover and adapted for operatively connecting the reciprocating member to a pump or the like to be driven by said apparatus.

15. In a pump operating apparatus, an enclosure adapted to contain oil, a cover therefor, driving mechanism including a slide operating through said cover, a bell-crank lever associated with the slide and depending from said cover, a crank adapted to operate said slide through said bell-crank lever, a drive shaft connected with said crank, and means for connecting the slide with a pump or the like to be driven, said lever, crank and shaft being disposed in self-oiling relation in said enclosure.

16. In a power head, an enclosure, a supporting element associated with the enclosure, mechanism suspended from, and removable as a unit with, said element, the mechanism comprising a worm, a shaft, a worm wheel thereon, a crank on each side of said wheel, a slide for each of said cranks, connecting means between said cranks and said slides, slide guides attached to said supporting element, and means for connecting said slides to driven apparatus.

17. In a pump operating mechanism, a housing therefor, a supporting member for said mechanism forming a removable element of said housing, said mechanism depending from said member, and comprising a worm, a shaft, a worm wheel thereon, a crank on each side of said wheel, a slide for each of said cranks, bell-crank levers between said cranks and said slides, slide guides attached to said supporting member, a motor carried by said supporting member for driving said worm, and means for operatively relating said slides with a pump or the like to be driven by said mechanism.

18. In a pump operating mechanism, a bifurcated chamber base adapted to serve as

an oil container for the mechanism, a cover for said chamber having an opening substantially between the furcations of said base, a motor carried on said cover, driving gearing 5 operated by the motor and suspended below the cover, and adapted to be lubricated by oil in the chamber base, said motor and driving gearing being adapted for ready removal with said cover.
